HEATER HOUSING FOR HAIR CURLERS

Giovanni Giacchero, 3 Corso Re Umberto,
Turin, Italy

Filed May 13, 1966, Ser. No. 2,285

Claims priority, application Italy Jan. 10, 1966

Term of patent 14 years

(Cl. D86—10)

FIGURE 1 is a front perspective view of a heater housing for curlers showing my new design, the broken line showing of curlers being for purposes of illustration only.

I claim:

The ornamental design for a heater housing for hair curlers, as shown and described.
